United States Patent Office

Des. 185,175
Patented May 12, 1959

185,175

FAN

Peter Schlumbohm, New York, N.Y.

Application December 30, 1958, Serial No. 53,984

Term of patent 14 years

(Cl. D26—7)

FIG. 1

FIG. 2

Fig. 1 is a perspective view of a fan showing my new design.

Fig. 2 is a top plan view thereof.

This application is a continuation-in-part of my co-pending companion application, Ser. #D-43,019, filed September 20, 1956, now abandoned.

I claim:

The ornamental design for a fan, as shown.
